UNITED STATES PATENT OFFICE.

HARRY T. BROCKMAN, OF CLEVELAND, OHIO.

DESIGN FOR A GRAVE-MARKER.

44,746.

Specification for Design.

Patented Oct. 21, 1913.

Application filed June 30, 1913. Serial No. 776,704. Term of patent 7 years.

To all whom it may concern:

Be it known that I, HARRY T. BROCKMAN, citizen of the United States, residing at Cleveland, in the county of Cuyahoga and State of Ohio, have invented a new, original, and ornamental Design for a Grave-Marker, of which the following is a specification, reference being had to the accompanying drawing, forming part thereof.

The present invention has for its object to provide an appropriate design for a grave-marker to be used upon the graves of deceased members of the Loyal Order of

Moose, and consists in a design as shown in the accompanying drawing, in which—

Figure 1 is a front elevation of a grave-marker, showing my new design. Fig. 2 is a rear elevation of the same.

I claim:

The ornamental design for a grave marker, as shown and described.

HARRY T. BROCKMAN.
